(57) CLAIM

The ornamental design for a shoebox, as shown and described.

DESCRIPTION

FIG. 1 is a first perspective view of a shoebox showing my new design;

FIG. 2 is a second perspective view;

FIG. 3 is a perspective view of the shoebox, shown in a folding state;

FIG. 4 is a front view of the shoebox of FIG. 1;

FIG. 5 is a rear view of the shoebox of FIG. 1;

FIG. 6 is a left side view of the shoebox of FIG. 1;

FIG. 7 is a right side view of the shoebox of FIG. 1;

FIG. 8 is a top view of the shoebox of FIG. 1;

FIG. 9 is a bottom view of the shoebox of FIG. 1; and,

FIG. 10 is an enlarged view of the selected portion "10" in FIG. 1.

Any shading and cross-hatching are not features of the design but are utilized to illustrate the surface contours of the shoebox in the drawings. The dash broken lines shown in the drawings depict portions of the shoebox that form no part of the claimed design. The broken lines encircling portions of the shoebox in FIG. 1 and shown in the enlarged view in FIG. 10 form no part of the claimed design.

1 Claim, 10 Drawing Sheets
